HONING MACHINE

Franklyn P. Hegeman, Union, N. J., assignor to
General Motors Corporation, Detroit, Mich., a
corporation of Delaware

Application June 11, 1948, Serial No. 32,320

16 Claims. (Cl. 51—59)

1

This invention relates to honing machines and is illustrated by way of example as constructed for honing the peripheral surfaces of conical rollers. An object of the invention is to provide an improved honing machine for finishing the peripheral surfaces of round work pieces. Another object is to provide improved apparatus for controlling the introduction and removal of work pieces to and from their honing positions. Another object is to provide an improved mounting for a hone, as to enable it to tilt and conform to the work surface as it reciprocates.

To these ends and also to improve generally upon machines of this character, the invention consists in the various matters hereinafter described and claimed. In the drawings

Fig. 1 is a plan view with certain honing mechanism removed and with a support in section.

Fig. 2 is chiefly a front view of Fig. 1, the hone carrier and associated parts being added.

Fig. 3 is a perspective view.

Figs. 4 and 5 are perspective views with different parts removed or displaced to reveal other parts.

Fig. 6 is a front view of the loading block partly in section.

Fig. 7 is an exploded view of the hone holder and its carrier in perspective.

Fig. 8 is a vertical section of Fig. 9 one of the carrier cheeks being removed and Fig. 9 is a horizontal section of Fig. 8.

Referring first to important elements and functions, work pieces W, herein shown as tapered rollers, are supplied, large and foremost, by any suitable feeding mechanism to a hollow loading block 2 from which they are intermittently released onto a hardened work rest 4 for a honing operation by a reciprocating hone 10. The work is rotated by engagement with a pair of driven rolls 6 and 8 and is released after honing by an ejector blade 12 which normally lies between the driven rolls but is advanced simultaneously with the retraction of the hone. An escapement mechanism releases a new roller onto the ejector blade and, upon retraction of the blade accompanied by advance of the hone, the new roller is dropped from the blade onto the work rest.

The driven rolls 6 and 8 are each secured by a washer 14 and a bolt 16 to a vertical spindle 18 suitably journaled in a quill 20 on a support 22. The rolls are driven in the same direction about their axes as by mechanism disclosed in patent to Hutchinson 2,433,455 except that it is preferred that the spindles be parallel instead of skewed. A ring 24 on the quill 20 has a flange projecting into a circular groove of each driven roll to exclude grit.

The loading block 2 is welded or brazed to the end of a slotted plate 26 adjustably secured by screws 28 to a clamping plate 30 on the rim 32

2

of the support 22. Each side of the loading block has a pair of vertically perforated lugs 34 each holding the upper end of a spring wire 36 which projects downwardly beyond the lower end of the loading block. The wires are guided in slits 38 at opposite sides of the loading block and their lower ends are closer together than the diameter of the work. It will be noted that the lugs and wires are offset from the center of the loading block. Hence the wires will act to urge the work piece into contact with the driven rolls but they can be spread apart to release a finished roller when the blade 12 is advanced.

The loading block has an opening 40 through which a lug 42 on a lever 44 is normally projected to support the column of rollers. The lever 44 is pivoted at 46 in a fork at the end of an arm 48 fixed on the bottom of the plate 26. The lever and lug are urged to holding position by a coil spring 50 attached to an upright lug 52 on the lever and to the plate 26. An adjusting screw 54 on a short upright lug of the lever will engage the loading block to limit the entry of the lug 42 through the opening 40. The upper portion of the lug 52 lies in the path of a screw 56 adjustably secured to an offset arm 58 on an upright bar 60 which is secured by plates 62 to a slide 64. The lower end of the bar 60 passes through the slotted plate 26 and is slotted to receive the ejecting blade 12. The slide 64 is shiftable along a fixed slideway 66 by means of a piston and cylinder unit 68. The slide carries the honing tool and appurtenances.

The hone 10 has its forward end curved to fit the work and it is clamped by a headed screw 70 in a split block or hone holder 72. The holder fits freely between forwardly projecting cheeks on a carrier 74, the cheeks having V-shaped recesses 76 in which bear the sharp edges of lugs 78 projecting from the hone holder. The sides of each recess 76 make a larger angle than the sides of each lug 78 so that the hone holder is capable of rocking movement to a limited extent. The lugs and recesses are kept seated by means of a projection 80 on the hone holder connected by a coil spring 82 to a cross pin 84 on the carrier. The carrier is bored out to receive the spring and the projection. One of the cheeks of the carrier has a slot 85 of greater width than the head of the clamping screw 70 to allow rocking of the hone holder.

The carrier 74 is brazed to the lower end of a sleeve 88 which is adjustably secured by set screws to the lower end of a reciprocating rod 90 passing through a guide bearing 92 on the slide 64 and reciprocated through a short stroke by any suitable crank mechanism 94 mounted on the slide. Thus the honing mechanism is shiftable towards the work simultaneously with the retreat of the blade 12 away from the work and is shift-

able away from the work as the blade advances towards the work. The work rest 4 is formed on the top of an upright blade carried by a slotted base 96 which is adjustably secured to the support 22. In the illustrated construction the work W consists of tapered rollers and the driven rollers 6 and 8 are conical to support the work with its axis in a vertical position. The rod 90 reciprocates at a slight angle to the vertical to carry the hone lengthwise along the work. The apparatus is adaptable to hone cylindrical work in which case the driven rolls are cylindrical and the hone is reciprocated parallel to the roll axes.

In operation, with a roller on the work rest, the hone is reciprocated for a timed interval whereupon the slide 64 is retracted. As the hone moves away from the work, the blade 12 pushes the work off the rest, the work spreading the wire springs 36. As this occurs, the screw 56 engages the lug 52 and withdraws the lug 42 from the loading block thereby releasing the next roller which drops upon the blade 12 temporarily. The slide 64 then advances, first allowing the coil spring 50 to project the lug 42 into the loading block to clamp the column of work pieces. Further advance of the slide causes the blade 12 to ride out from beneath the piece and drop it upon the work rest, the wire springs insuring contact of the work with the driven rolls as the hone makes contact with the work. The rockable mounting of the hone causes it to seat itself and conform to the work.

I claim:

1. In a honing machine having a pair of rotatable rolls to engage the periphery of a round work piece and a work rest to engage and support one end of the work piece, a blade extending between the rotatable rolls, a hone in opposed relation to the blade, mechanism for reciprocating the hone lengthwise of the work piece, a slide forming a common support for said mechanism and said blade, and means for shifting the slide to withdraw the hone from the work and advance the blade across the work rest to expel a finished piece.

2. In a honing machine having a pair of rotatable rolls to engage the periphery of a round work piece and a work rest to engage and support one end of the work piece, a blade extending between the rotatable rolls, a hone in opposed relation to the blade, mechanism for reciprocating the hone lengthwise of the work piece, a slide forming a common support for said mechanism and said blade, means for shifting the slide to withdraw the hone from the work and expel a finished piece from the work rest, a hollow loading block to guide a column of work pieces in line with the work rest, and means actuated by the slide for releasing a new work piece from the loading block.

3. In a honing machine having a pair of rotatable rolls to engage the periphery of a round work piece and a work rest to engage and support one end of the work piece, a blade extending between the rotatable rolls, a hone on the opposite side of the work rest from the blade, a hollow loading block to guide a column of work pieces in line with the work rest, mechanism for reciprocating the hone lengthwise of the work piece, a detent for supporting a supply of work pieces in the loading block, a common support for said reciprocating mechanism and said blade, means for shifting the common support to withdraw the hone from the work and advance the blade between the work rest and the loading

block, and means carried by said common support for actuating the detent to release a work piece onto said blade.

4. In a honing machine having a pair of rotatable rolls to engage the periphery of a round work piece and a work rest to engage and support one end of the work piece, a blade extending between the rotatable rolls, a hone in opposed relation to the blade, mechanism for retracting the hone from the work and advancing the blade across the work rest, a hollow loading block to guide a column of work pieces in line with the work rest, a pair of spaced spring members for guiding a work piece from the loading block to the work rest, said springs normally being spaced apart a distance less than the diameter of a work piece and adapted to be spread apart when the blade expels a finished work piece from the work rest.

5. In a honing machine having a pair of rotatable rolls to engage the periphery of a round work piece and a work rest to engage and support one end of the work piece, a hollow loading block to guide a column of work pieces in line with the work rest, a pair of spring members for guiding a work piece from the loading block to the work rest, said spring members being offset from the center of the loading block and having their terminal portions closer together than the diameter of a work piece to urge a work piece into contact with the rotatable rolls, a blade, and means for projecting the blade across the work rest to expel a work piece between the spring members.

6. In a honing machine having a pair of rotatable rolls to engage the periphery of a round work piece and a work rest to engage and support one end of the work piece, a hollow loading block to guide a column of work pieces in line with the work rest, a pair of spring members offset from the center of the loading block and extending towards the work rest, the sides of the loading block having slits to receive intermediate portions of the spring members, and the terminal portions of the spring members being closer together than the diameter of a work piece to retain the latter in contact with the rotatable rolls.

7. In a honing machine having a pair of rotatable rolls to engage the periphery of a round work piece and a work rest to engage and support one end of the work piece, a hollow loading block to guide a column of work pieces in line with the work rest, and a pair of spaced spring members for guiding a work piece from the loading block to the work rest, said spring members being offset from the center of the loading block and being closer together than the diameter of a work piece to urge the work piece towards the driven rolls.

8. In a honing machine having a pair of rotatable rolls to engage the periphery of a round work piece and a work rest to engage and support one end of the work piece, a hollow loading block in line with the work rest to guide a column of work pieces thereto, a blade adapted to be advanced between the loading block and the work rest to expel a work piece from the rest, a reciprocating slide for advancing and retracting the blade, a detent for supporting work pieces in the loading block, means actuated by advance of the blade for releasing the detent to drop a work piece onto the blade, and a spring for moving the detent to holding position as the blade is retracted to release the work piece onto the rest.

9. In a honing machine having a pair of rotat-

able rolls to engage the periphery of a round work piece and a work rest to engage and support one end of the work piece, a hollow loading block in line with the work rest to guide a work piece thereto, a hone, mechanism for reciprocating the hone lengthwise of the work piece, a slide supporting said mechanism, a spring-pressed detent for holding work pieces in the loading block, and means for shifting the slide to retract the hone from the work, expel a finished work piece and move the detent from holding position to release a new work piece from the loading block.

10. In a honing machine having means to support and rotate a round work piece on its axis, a hone, a pair of hone mounting members connected together for relative rocking movement, one member having a pair of projecting cheeks embracing a portion of the other member to prevent lateral movement, the cheeks having angular recesses, the other member having projections with edges to seat in the recesses, the sides of each recess defining a larger angle than the sides of the projections, a spring connecting the members together to hold the projections and recesses in seated relation, means for clamping the hone to one of the members, and reciprocating mechanism connected to the other member to actuate the hone along the work piece.

11. In a honing machine having means to support and rotate a round work piece on its axis, a hone, a pair of relatively rockable members, one member having a pair of recesses and the other member having a pair of projections to seat in the recesses and rock therein, a spring connecting the members together to hold the projections and recesses in seated relation, means for clamping the hone to one of the members, and mechanism for reciprocating the other member in a direction to traverse the hone lengthwise of the work piece.

12. In a honing machine having means to support and rotate a round work piece on its axis, a pair of relatively rockable members, one member having a recess and the other member having a projection to seat in the recess and rock therein, a spring connecting the members together to hold the projection seated in the recess, a hone, means for clamping the hone to one of the members, mechanism for reciprocating the other member in a direction to traverse the hone lengthwise of the work piece, and means for preventing relative movement of the members laterally of the work piece.

13. In a honing machine having a pair of driven rolls rotatable in a horizontal plane, a work rest

and a work loading block in vertical alignment with each other and offset to one side of the plane of the roll axes, means for feeding round work pieces in succession from the loading block to the work rest, a hone, mechanism for reciprocating the hone lengthwise of the work, and a slide carrying said mechanism for causing the hone to press against the work and urge it into rotating contact with the driven rolls.

14. In a honing machine having a pair of driven rolls, a work rest and a work loading block in alignment with each other and offset to one side of the line of roll centers, means for feeding round work pieces in succession from the loading block to the work rest, a hone, a mechanism for reciprocating the hone lengthwise of the work, and means for pressing the hone against the work to hold the work in rotating contact with the driven rolls.
15. In a honing machine having a pair of driven rolls, a work rest and a work loading block in alignment with each other and offset to one side of the line of roll centers, means for feeding round work pieces in succession from the loading block to the work rest, a hone, mechanism for reciprocating the hone lengthwise of the work, said mechanism including a rockable mounting for the hone to provide for self-conforming contact of the hone with the work, and means for pressing the hone against the work.
16. In a honing machine having a pair of driven rolls, a work rest and a work loading block in alignment with each other and offset to one side of the line of roll centers, means for feeding round work pieces in succession from the loading block to the work rest, a hone, mechanism for reciprocating the hone lengthwise of the work, a slide carrying said mechanism for moving the hone towards or from the work, and a blade connected to the slide and actuated thereby to project the blade between the driven rolls and across the work rest.
